UNITED STATES PATENT OFFICE.

JESSE F. ETCHEISON, OF CLOVIS, NEW MEXICO.

WINDOW CONSTRUCTION.

1,348,700.

Specification of Letters Patent.

Patented Aug. 3, 1920.

Application filed September 30, 1919. Serial No. 327,369.

To all whom it may concern:

Be it known that I, JESSE F. ETCHEISON, a citizen of the United States, residing at Clovis, in the county of Curry and State of New Mexico, have invented new and useful Improvements in Window Construction, of which the following is a specification.

This invention relates to window constructions and has for its object the provision of a window mounting whereby a window may be swung slightly inwardly upon its lower edge for purpose of ventilation and so that the window will be supported in inclined position deflecting currents of air upwardly toward the ceiling where most needed, the window being furthermore so constructed that the lower edge thereof may be connected with the upper edge of the window frame and the window be disposed entirely open and in horizontal position projecting inwardly into a room or the like from the upper edge of the frame.

An important object is the provision of a window construction of this character provided at its lower edge with a peculiarly constructed lifting member, portions of which extend through the sash and are formed to provide an eye engageable upon a hook at the top of the window frame when the window is in raised position.

Another object is the provision of a novelly constructed sliding catch member disposed at the top of the sash and engageable with the frame for holding the window in closed position.

An additional object is the provision of a window construction of this character in which the sash may be quickly and easily moved into any one of three possible positions, and in which the construction will be simple and inexpensive in manufacture, highly efficient and durable in use, and a general improvement in the art.

With the above and other objects and advantages in view, the invention consists in the details of construction to be hereinafter more fully described and claimed, and illustrated in the accompanying drawings in which—

Figure 1 is a front elevation of my window structure,

Fig. 2 is a rear elevation thereof, with the window in closed position,

Fig. 3 is a longitudinal sectional view with the window in closed position,

Fig. 4 is a similar view showing the window tilted inwardly.

Fig. 5 is a similar view showing the window raised into open position,

Fig. 6 is a detail elevation of the lifting member and hook formed thereon,

Fig. 7 is a perspective view of one of the hangers, and

Fig. 8 is an enlarged elevation of the sliding catch member.

Referring more particularly to the drawings, the letter A designates a portion of the wall of a room or the like provided with a window frame B. This frame is provided on the inner faces of its sides and top with stop strips 10 and a transverse strip 11 is provided at the inner side of the wall and projecting above the sill C.

Associated with the frame B is a sash D of ordinary construction which is provided at its upper corners with hinged hangers 12 with which are connected cords or the like 13 which are connected with the ceiling of the room or other inclosure. These hangers are preferably formed of strips 14 secured upon the sash and having their terminals formed as eyes 15 within which are engaged yokes 16 to which the cords are connected.

Disposed upon the inner face of the top rail of the sash is a sliding catch structure which is formed as a single length of wire bent to provide a central tongue 17 adapted to be projected into the recess 18 in the top of the window frame, and further bent to provide guide arms 19 disposed at the sides of the tongue. The wire forming this catch member is also bent, as shown, to provide a handle 20 which projects from the inner face of the sash. This catch member is held in position by a suitable housing 21 formed preferably of sheet metal and provided with an opening 22 in its upper edge through which the tongue 17 projects. The housing 21 is secured upon the sash by screws 23 and 24, the latter of which is disposed between the sides of the tongue 17 to form a guide and also a stop for limiting retraction of the tongue. Also secured upon the upper edge of the frame is a depending hook 25, for a purpose to be described.

Secured upon the bottom rail of the sash is a lifter member, designated broadly by the numeral 26, and this lifter member is formed preferably of wire bent into shape and includes a pair of spaced arms 27 and 28 which extend through holes formed in

the sash, and the lowermost arm 28, has its extremity coiled upon itself, as shown, to provide an eye 29 which projects beyond the outer face of the sash. The arm 27 after 5 passing through the sash is bent downwardly at right angles and is coiled about the arm 28. This lifter member further includes an arm 30 which extends through the sash and which has its terminal downwardly bent, as shown. The lifter member 10 is also formed to provide a handle 31 which projects beyond the inner face of the sash.

In the operation of the window, when it is desired to close the same, the sash is disposed with its lower edge outwardly of the strip 11 and the upper edge is then swung outwardly so that the sash will be disposed entirely within the frame B in engagement with the strips 10 thereon. The catch member 15 at the top of the sash is then manipulated to project the tongue 17 into the recess 18 and the sash will thus be locked in closed position.

When it is desired to open the window 20 partially for purposes of ventilation, it is merely necessary that the operator pull down upon the handle 20 to withdraw the tongue 17 from the recess 18, whereupon the sash will swing inwardly upon its bottom 25 edge, as a fulcrum, the swinging movement being limited by tautening of the cords 13. Air entering through the window will, upon striking the sash be deflected upwardly so as to produce thorough ventilation and at 30 the same time rain will be excluded.

When it is desired to open the window entirely, the sash is first moved to its tilted position, as just described, after which the operator grasps the lifter member 26 and 35 raises the bottom edge of the sash to the top of the frame, whereupon the eye 29 is engaged upon the hook 25. The sash will thus be held in raised position with the window opening entirely unobstructed.

From the foregoing description and a 40 study of the drawing it will be apparent that I have thus provided a simple, inexpensive, and easily constructed window and

mounting therefor which is capable of a variety of adjustments with the utmost ease 50 and it will also be apparent that the construction will efficiently perform all the functions for which it is designed.

While I have shown and described the preferred embodiment of my invention it is 55 of course to be understood that I reserve the right to make such changes in the form, construction, and arrangement of parts as will not depart from the spirit of the invention or the scope of the subjoined claims. 60

Having thus described my invention, I claim:

1. In combination with a window frame and a sash adapted to fit within the same, a mounting system for the sash comprising 65 hangers disposed at the upper corners of the sash, cords connected with said hangers and secured at a point above the frame whereby to support the sash in inwardly inclined position with the bottom rail thereof engaged upon the sill of the frame, a lifter member at the lower rail of the sash, a securing member on the lower rail of the sash, and a securing member at the top of the frame engageable by said first named securing member for holding the sash in inwardly extending horizontal position at the top of the frame.

2. In combination with a window frame and a sash adapted to fit within the same, 80 a mounting system for the sash comprising hangers disposed at the upper corners of the sash, cords connected with said hangers and secured at a point above the frame whereby to support the sash in inwardly inclined position with the bottom rail thereof engaged upon the sill of the frame, a lifter member at the lower rail of the sash provided with an eye, and a hook disposed at the upper edge of the frame and engageable by said eye whereby to hold said sash in elevated position extending horizontally inwardly at the top of the frame. 90

In testimony whereof I affix my signature.

JESSE F. ETCHISON.
